UNITED STATES PATENT OFFICE.

JOHN G. SNYDER, OF ALTOONA, PENNSYLVANIA.

METALLIC RAILWAY-TIE.

No. 921,297.

Specification of Letters Patent.

Patented May 11, 1909.

Application filed August 5, 1907. Serial No. 337,249.

To all whom it may concern:

Be it known that I, JOHN G. SNYDER, a citizen of the United States, residing at Altoona, in the county of Blair and State of

5 Pennsylvania, have invented certain new and useful Improvements in Metallic Railway-Ties, of which the following is a specification.

10 My invention relates to improvements in railroad-ties, and the object is the provision of a railroad-tie which will be very durable and have a very long life, rendering the tie more desirable and economical, all matters considered, than the ties in general use.

15 Another object of my invention is the provision of a railroad-tie which will form a perfect support for the rails, having resiliency and adherence, insuring a tie combining every requisite to render the same thoroughly practical and efficient in every particular.

20 To attain the desired object, my invention consists of a railroad-tie embodying novel features of construction and combination of parts, substantially as described.

25 Figure 1, is a longitudinal perspective view of my tie. Fig. 2, is a plan view of the tie with two of the clamping members removed; and Fig. 3, is an end view of the same showing the filling held between the inturned flanges.

30 In the drawings letter A, designates the body of my tie, which is constructed "I-beam" in shape, with the edges of the bottom flanges B, B, turned down and in as designated at C, C, forming a longitudinal open bottom D, adapted to contain a filling to give the tie resiliency and adherence. The bottom of the tie is constructed somewhat wider than the crown or top of the same to allow 35 flanges B, B, to be turned down and in to form retaining means for the filling K, (shown in Fig. 8), which spreads over a considerable area of the road-bed, allowing the same to unite with the material of said road-bed, thus holding the tie against movement.

40 Means are provided for fastening the rail to the tie. On each side of the rail are clamps E, E, fitting over the foot and abutting against the web of the rail below its 45 crown, which are provided with downwardly extending tongues F, F, formed on each side and at the outer end of the same, which enter slots G, G, formed and entering transversely from the edges of the face or crown

of the tie; longitudinally therewith along the 55 face of the tie are bolt receiving openings H, H, to receive the bolts to fasten the said clamps to the tie.

From the foregoing description, taken in connection with the drawing, it is evident 60 that I provide a railroad-tie which although much more expensive than the wood tie will last for so long a time as to make it really cheaper than the ordinary tie; also, that the tie forms a perfect support for the rails, and 65 provided with an elastic filling will have resiliency to insure smooth and even movement of heavy loaded and fast running trains passing over the same.

Having thus described my invention, what 70 I claim, is:

1. A metallic railroad-tie, constructed "I-beam" in shape, having the edges of its base turned down and in, forming a longitudinal open bottom, adapted to contain a 75 filling, and means for fastening the rail to the tie, substantially as described.

2. An I-beam having two of its opposite edges turned downward and then curved inward toward each other. 80

3. A tie provided with a flat top and bottom and having its lower edges directed downward and curved toward each other, filling material received between said edges, and means for securing the rails to the tie. 85

4. A railway tie of I-beam shape having its lower edges turned downward and inward, the rail adapted to be seated on the flat crown of the tie, there being recesses formed in the edges of the crown, and clamps to engage the foot of the rail having depending fingers to engage the recesses, and bolts securing the clamps in place. 90

5. A tie of I-beam shape having a flat crown and its lower edges turned downward 95 and curved inward, filling material retained between such inturned edges, there being recesses formed in the edges of the crown, clamps engaging the foot of the rails and having depending fingers to engage the recesses, and fastenings securing the clamps in place. 100

In testimony whereof I affix my signature in presence of two witnesses.

JOHN G. SNYDER.
